UNITED STATES PATENT OFFICE.

ALBERT CONWAY SMITH AND FRANCIS HAROLD SMITH, OF HINCKLEY, ENGLAND.

COLLAR IRONING AND SHAPING MACHINE.

1,216,507.

Specification of Letters Patent. Patented Feb. 20, 1917.

Application filed July 3, 1914. Serial No. 848,901.

To all whom it may concern:

Be it known that we, ALBERT CONWAY SMITH and FRANCIS HAROLD SMITH, subjects of the King of Great Britain, residing at 1 Trinity Vicarage road, Hinckley, in the county of Leicester, England, have invented certain new and useful Improvements in Collar Ironing and Shaping Machines, of which the following is a specification.

- 10 This invention relates to ironing and shaping machines for double or folded collars, of the kind having a rotary unheated cylindrical annular mandrel, on which the folded collar is placed, after the fold has 15 been damped, with the inside portion of the collar on the inside of the mandrel, and a heated rotating roller, which may be grooved, arranged at the edge of the mandrel and which bears against and irons the 20 fold of the collar.

According to the present invention, a machine of the above described kind is provided with a heated ironing tool which shapes the collar while it is still upon the 25 mandrel.

This ironing tool is arranged behind the fold-ironing roller on the inside of the mandrel, and preferably consists of a heated curved plate arranged parallel to the inner 30 surface of the mandrel and having its leading edge flared away from the mandrel to facilitate the entry of the collar between the plate and the mandrel.

The collar when ironed on the inside portion only, curls inwardly as the outside portion follows the curvature of the inside portion, whereas if the outside portion alone is ironed the curl would be in the wrong direction, *i. e.* outward, and if both the inside 40 and outside portions are ironed their tendencies to curl in opposite directions more or less neutralize one another.

Some double collars have button-hole tabs, the upper edges of which protrude above the folds of the collars and would become crushed if acted upon by the fold-ironing roller. A guard-plate is therefore arranged in front of the roller at a position to be encountered by the protruding portion 50 of such a tab, which latter thereby becomes diverted to one side of, and is not acted upon, by the roller. This diverting plate also constitutes a finger guard for the heated roller.

55 A roller may be provided on the outside of the mandrel, for the purpose of pressing

down the outer portions of collars composed of such thick and unpliant material that the fold thereof would otherwise be unduly wide. This roller is not an ironing roller, 60 being unheated, and is preferably wooden.

With a grooved fold-ironing roller, the flange on the outside of the mandrel should be sufficiently remote therefrom not to bear upon and mark the outside of the collar. 65

An example of a machine according to the present invention is illustrated on the accompanying drawings, in which:—

Figure 1 is a sectional elevation, and Fig. 2 is a plan.

a is an unheated cylindrical annular mandrel, rotatably mounted on a vertical spindle *b*, and provided with a worm-wheel *c*. This worm-wheel *c* is driven by a worm *d*, secured on a horizontal shaft *e*, on which 75 is a loose driving pulley *f*. The loose pulley *f* is connected to the shaft *e*, by means of a clutch-piece *f*¹ on the pulley *f*, which engages with a clutch-piece *e*¹ on the shaft *e*, on depression of a lever *g*, a tooth *g*¹ of 80 which is thereby caused to ride out of a notch in the bearing *h* of the shaft *e*, and in so doing displaces the lever *g* and pulley *f* to the right against the influence of a spring *i*. 85

j is a grooved roller, heated by a gas-burner *k*, and secured on a horizontal spindle *j*¹. The roller *j* is yieldingly pressed against the edge of the mandrel *a* by means of a spring *l*.

A curved ironing-plate *m* is mounted behind the roller *j*, on the inside of the mandrel *a*, by means of a stem *m*¹, sliding in a socket *n*, secured to the upper end of the spindle *b*. A spring *n*¹ in the socket *n* 95 presses the ironing-plate *m* against the inside of the mandrel *a*. The plate *m* is heated by a gas-burner *o* and its leading edge is flared away from the mandrel *a*, to facilitate the entry of collars between same. 100

A freely rotating wooden roller *p*, pressed by a spring *p*¹ against the mandrel *a*, is mounted on the outside of the latter behind the heated fold-ironing roller *j*.

A switch-plate *q* is arranged in the known manner with its edge in close proximity to the mandrel *a*, some distance behind the ironing-plate *m* and wooden roller *p*.

A guard-plate *r* is secured immediately in front of the roller *j*, closely above and diagonally across the edge of the mandrel *a*. 110

The spindle *j*¹ of the fold-ironing roller *j*

is driven through a train of spur-wheels and pinions *s*, *t*, *u*, by a pinion *v* on the pulley-driven shaft *e*.

The machine operates as follows:—

5 The gas-burners *k* and *o* being alight and heating the fold-ironing roller *j* and the inside ironing-plate *m*, a collar, the fold of which has been damped for instance by passing same over a flattened nozzle from which 10 steam issues, is placed on the rotating mandrel *a*, with the inside portion of the collar on the inside of the mandrel. The collar is carried by the mandrel beneath the fold-ironing roller *j*, whereby the fold becomes 15 ironed. Should the collar have an upwardly protruding tab, this is thrust on one side by encountering the guard-plate *r* so as not to pass beneath the roller. On issuing from beneath the roller *j* the collar is carried 20 by the mandrel *a* past the heated ironing-plate *m*, whereby the inside portion of the collar is ironed between the plate *m* and the mandrel, and acquires an inward curl, to which the outside portion of the collar conforms. At the same time the outside portion 25 of the collar passes in contact with the wooden roller *p*, whereby the outside portion of the collar if somewhat spread away from the mandrel is pressed inward against same. After this, the collar, carried by the 30 mandrel, encounters the leading end of the switch-plate *q* and, by riding up same, is thrown off the mandrel.

We claim:—

35 1. In an ironing and shaping machine for turn-down collars, a collar-supporting member having a creasing edge adapted to be straddled by the collar in a folded condition, an ironing member having crease-ironing surfaces adapted to contact with the crease of a collar mounted on the supporting member, one of the said members being movable with respect to the other, and means for bending any collar tab which projects past 40 the creasing edge of the supporting member laterally when in close proximity to the ironing member to avoid the crease-ironing surfaces of the latter without disturbing the position of the collar as a whole.

45 2. In an ironing and shaping machine for turn-down collars, a collar-supporting member having a creasing edge adapted to be straddled by the collar in a folded condition, an ironing member having crease-ironing surfaces adapted to contact with the crease of a collar mounted on the supporting member, one of the said members being movable with respect to the other, and a tab-bending member extending obliquely 50 across the creasing edge of the supporting member in advance of the said ironing member and being mounted in fixed relation to the latter.

55 3. In an ironing and shaping machine for turn-down collars, a collar-supporting mem-

ber having a creasing edge adapted to be straddled by the collar in a folded condition, an ironing member having crease-ironing surfaces adapted to contact with the crease of the collar mounted on the supporting member, one of the said members being movable with respect to the other, the ironing member also having a guard flange projecting inwardly past the creasing edge of the supporting member at one side of the same, 70 and a tab-bending member extending obliquely across the creasing edge of the supporting member immediately in advance of the ironing member and being mounted in fixed relation to the latter, the end of the tab-bending member which is nearer to the ironing member being disposed substantially flush with the side of the guard flange of the latter opposite to the creasing edge of the supporting member. 75

80 4. In an ironing and shaping machine for turn-down collars, a rotatable collar-supporting mandrel having an annular creasing edge adapted to be straddled by the collar in a folded condition and with its inner fold disposed on the inside of the mandrel to support the collar crease throughout its entire length, an ironing member having crease-ironing surfaces adapted to contact with the crease of a collar mounted on the 90 mandrel, and a shaping member mounted stationarily within the mandrel in rear of the crease-ironing member for contact with the inner fold of the collar as it leaves the latter. 95

100 5. In an ironing and shaping machine for turn-down collars, a rotatable collar-supporting mandrel having an annular creasing edge adapted to be straddled by the collar in a folded condition and with its inner fold disposed on the inside of the mandrel to support the collar crease throughout its entire length, an ironing member having crease-ironing surfaces adapted to contact with the crease of the collar mounted on the 105 mandrel, a shaping member mounted stationarily within the mandrel in rear of the crease-ironing member for contact with the inner fold of the collar as it leaves the latter, and a holding member mounted outside the creasing edge of the mandrel and radially opposite to the shaping member for contact with the outer fold of the collar. 110

115 6. In an ironing and shaping machine for turn-down collars, a rotatable collar-supporting mandrel having an annular creasing edge adapted to be straddled by the collar in a folded condition and with its inner fold disposed on the inside of the mandrel to support the collar crease throughout its 120 entire length, an ironing member having crease-ironing surfaces adapted to contact with the crease of the collar mounted on the mandrel, a shaping member mounted stationarily within the mandrel in rear of the 125

130

crease-ironing member for contact with the inner fold of a collar as it leaves the latter, and means for ejecting the collar from the mandrel after it has passed the ironing and shaping members.

7. In an ironing and shaping machine for turn-down collars, a rotatable collar-supporting mandrel having an annular creasing edge adapted to be straddled by the collar in a folded condition and with its inner fold disposed on the inside of the mandrel to support the collar crease throughout its entire length, an ironing member having crease-ironing surfaces adapted to contact with the crease of the collar mounted on the mandrel, a shaping member mounted stationarily within the mandrel in rear of the crease-ironing member for contact with the inner fold of the collar as it leaves the latter, and a switch plate mounted at a position in rear of the shaping member and having a vertically inclined edge extending past the creasing edge of the mandrel and disposed in such proximity to the latter that it will project between the folds of each collar as it approaches.

8. In an ironing and shaping machine

for turn-down collars, a rotatable collar-supporting mandrel having an annular creasing edge adapted to be straddled by the collar in a folded condition and with its inner fold disposed on the inside of the mandrel to support the collar crease throughout its entire length, an ironing member having crease-ironing surfaces adapted to contact with the crease of a collar mounted on the mandrel, a shaping member mounted stationarily within the mandrel in rear of the crease-ironing member for contact with the inner fold of a collar as it leaves the latter, and means for bending any collar tab which projects past the creasing edge of the mandrel laterally when in close proximity to the ironing member to avoid the crease-ironing surfaces of the latter without disturbing the position of the collar as a whole.

In testimony whereof we affix our signatures in presence of two witnesses.
